DESIGN FOR A RADIO CABINET OR THE LIKE

Donal G. Erskine, Baltimore, Md., assignor to
Bendix Aviation Corporation, Towson, Md., a
corporation of Delaware

Application March 18, 1946, Serial No. 127,642

Term of patent 3½ years

(Cl. D56—4)

To all whom it may concern:

Be it known that I, Donal G. Erskine, a citizen of the United States, residing in Maryland, in the city of Baltimore, have invented a new, original, and ornamental Design for a Radio Cabinet or the like, of which the following is a specification, reference being had to the accompanying drawing, forming a part thereof.

In the drawing:

Figure 1 is a perspective view of a radio cabinet or the like, showing my new design:

Figure 2 is a front view thereof;

Figure 3 is a side view thereof.

The characteristic features of my design reside in the portions shown by means of full lines in the drawing.

What is claimed is:

The ornamental design for a radio cabinet or the like, as shown and described.

DONAL G. ERSKINE.
